COMBINED DISPENSER FOR STRIP MATERIAL AND HOLDER THEREFOR

Robert Glenn, 70-20 108th St.,
New York, N.Y. 10025

Filed Jan. 13, 1969, Ser. No. 15,329

Term of patent 14 years

Int. Cl. D9—04

U.S. Cl. D52—2

FIG. 1 is an exploded perspective view of a combined dispenser for strip material and holder therefor embodying my new design;

FIG. 2 is a front elevational view thereof;

FIG. 3 is a left side elevational view thereof;

FIG. 4 is a right side elevational view thereof;

FIG. 5 is a rear elevational view thereof;

FIG. 6 is a top plan view thereof; and,

FIG. 7 is a bottom plan view thereof.

I claim:

The ornamental design for a combined dispenser for strip material and holder therefor, as shown.
